OUTLET FOR AIR CIRCULATING SYSTEMS

Herbert F. Curtis, Berea, Ohio, assignor to The Henry Furnace & Foundry Company, Cleveland, Ohio, a corporation of Ohio

Application November 29, 1935, Serial No. 52,062

5 Claims. (Cl. 98—114)

This invention relates to improvements in outlets for air circulating systems.

One of the objects of the invention is the provision of means for readily mounting an outlet box or body member upon the studding of a building.

Another object is the provision of suitable means for supporting the grill directly from the outlet box, and particularly by the aid of fastenings in the brackets which support the box.

A further object is the provision of means for preventing dirt and debris from entering the outlet box after it is installed in the framing of a new building.

15 Other objects and features of novelty will appear as I proceed with the description of that embodiment of the invention which, for the purposes of the present application, I have illustrated in the accompanying drawings, in which

20 Fig. 1 is a perspective view of an outlet box embodying the invention.

Fig. 2 is a perspective view of a temporary cover for such a box.

25 Fig. 3 is a front elevational view of the box with its grill in place thereon.

Fig. 4 is a rear elevational view of the grill, and

30 Fig. 5 is a perspective view on a smaller scale showing the cover in operative position.

The present invention has to do with outlets for air circulating systems generally, that is outlets which may be employed for air conditioning work as well as for heating, and so designed as to make the mounting and assembly of the unit a quickly and easily performed operation. As heretofore constructed the outlet box and the grill have been supported upon wooden framing pieces attached to the studding, which has naturally required some little time for cutting and fitting as well as for assembling. The present invention eliminates this work, providing metal brackets permanently attached to the outlet box which are adapted to be nailed to the studs on either side of the box, and are furthermore adapted to receive fastenings by means of which the grill is supported.

35 In the drawings the outlet box is shown as having end walls 10 and 11, a rear wall 12, and a front wall 13. Above the wall 13 there is a forwardly projecting rectangular outlet housing or casing formed partly by extensions on the end walls 10 and 11 and partly by a top wall 14 and a shelf 15. This casing is entirely open at the front. In the box there is a damper 16, which consists of a flat sheet of metal hinged at its

40 rear edge to the rear wall of the box. This sheet of metal is of the same length and width approximately as the vertical passage in the box, so that when it is down in a horizontal position the flow of air is cut off completely. In order that this damper may remain in any desired position of adjustment, spring fingers 17 are welded to it, and these fingers have curved extremities which are free to flex and bear frictionally against the end walls of the box. They are 10 adapted to yield when sufficient pressure is exerted to move the damper, but they prevent accidental movement. When a grill is in place upon the outlet it is of course impossible to grasp the damper and move it up or down, and in order 15 to make adjustments possible when the grill is in position I attach a small yoke 18 to the damper for engagement with a rod which may be projected through a hole in the grill and used to lift or depress the yoke. In order to definitely regulate the vertical location of the box when installed in a base board, I attach to the front wall 13 a small angle iron 9 which is adapted to engage the floor.

20 In the rear and front walls 12 and 13, although appearing in the front wall only in the accompanying drawings, lips 19 are struck outwardly and serve to cooperate with similar lips (not shown) on the vertical conduits with which the outlet is used. In this manner a locked connection between the outlet and its conduit is effected.

25 To each of the end walls 10 and 11 I rivet or weld a sheet metal bracket 20 of a gauge preferably somewhat heavier than that of the box proper. This bracket may be said to be channel shaped, with one long arm or flange 21 and one short flange 22. The arms 21 are long enough to project in front of and engage the studs of a building on either side of the outlet. Pairs of nail holes 23 are punched into these bracket 30 arms in position to correspond with different spacing of the studs. When the correct position of the outlet is determined and it is in place in that position, the operator merely drives two nails through each bracket arm 21 into the 35 studding, and the mounting of the outlet is completed.

40 The grill 24 is a heavy stamping perforated with numerous openings 25, with rearwardly extending flanges 26 and 27 along its upper and 45 side edges respectively. The side flanges 27 embrace the edges of the bracket flanges 22. On the rear side of the grill I build up an inner rectangular frame from a strip of metal bent lengthwise into angle form in cross section. One 50

flange 28 of the angle is spot welded to the grill, and the other flange 29 extends rearwardly at right angles to the grill. The four elements of this inner frame may be entirely separate, or 5 the flanges 29 may be continuous and merely bent at the corners, the flanges 28 being notched out at the corners. The latter construction is preferred. The flanges 29 are so positioned as 10 to fit fairly snugly within the outlet opening at the front of the box. A pair of screw holes 30 are punched in the grill between each pair of side flanges 27 and 29. When the grill is in position on the outlet box with the flanges 29 inside the outlet opening, the holes 30 come into 15 register with holes 31 formed in the bracket flanges 22. Screws are then inserted through the holes 30 and threaded into the holes 31 to hold the grill in place. It will be noted that the flanges 22 of the brackets are flush with the forward edges of the outlet opening. The rear surface of the grill rests against these flanges and the edges of the wall surrounding the outlet opening.

The grill 24 is furnished in a completely finished and decorated condition. In the ordinary construction of a building the outlet box is mounted before the lath and plaster are applied. If the grill were assembled onto the box at this time its finish would be subject to injury. It is 20 however undesirable to leave the box open because considerable dirt and debris would then get into it. In order to meet these conditions I provide an inexpensive tin cover 32 which completely excludes foreign matter and may be discarded after the building is completed, when the grill may be mounted on the box. The cover 32 is of a size to snugly fit within the outlet opening and is provided with forwardly offset flanges 33 to engage the front edge of the opening and 25 the front surfaces of bracket flanges 22. Friction alone may be depended upon to hold the cover in place, but if desired it may be secured by means of fastenings fitting the holes 31 in the brackets.

40 Variations from the described structure may be employed. Accordingly I desire it to be understood that the scope of the invention is to be regarded as defined exclusively by the appended claims rather than by the foregoing description or the accompanying illustrations.

Having thus described my invention, I claim:

1. In a wall outlet for air circulating systems, 45 a body member having a vertical outlet opening, and a pair of sheet metal brackets permanently

fastened to the side walls of the body member to constitute a part of the body member, said brackets comprising arms adapted to engage the surfaces of the studding on either side of the outlet and to be nailed thereto, and said brackets 5 also comprising flanges spaced forwardly from said arms adapted to receive and hold a grill.

2. In a wall outlet for air circulating systems, 10 a body member having a vertical outlet opening, and a pair of vertically arranged channel shaped sheet metal brackets, the webs of which are permanently secured to the side walls of said outlet adjacent the opening therein, thereby constituting a part of the body member the rear flange of the channel extending outwardly far enough 15 to engage the forward surfaces of the studding on either side of the outlet, and the forward flange having an opening therein adapted to receive a fastening for attachment of a grill.

3. In a wall outlet for air circulating systems, 20 a body member having a vertical outlet opening, and a pair of vertically arranged channel shaped sheet metal brackets, the webs of which are permanently secured to the side walls of said outlet adjacent the opening therein, thereby constituting a part of the body member as fabricated, 25 the rear flange of the channel extending outwardly far enough to engage the forward surfaces of the studding on either side of the outlet, the forward flange being flush with the forward 30 edge of the body member around said opening, each of said forward flanges also having an opening therein adapted to receive a fastening for attachment of a grill.

4. In a wall outlet for air circulating systems, 35 a body member having a vertical outlet opening, a flat sheet metal member permanently attached to each side wall of the body member extending outwardly therefrom and flush with the forward open end of the body member, a grill adapted to 40 be fitted over said outlet having rearwardly extending side flanges adapted to embrace said outwardly extending flat sheet metal members, and means for fastening said grill to said flat sheet 45 metal members.

5. In combination, an outlet box for air circulating systems, means for attaching a grill to the box, a damper within the box, friction means for holding the damper in various positions of adjustment, and a loop upon the damper adapted 50 to be engaged by a tool inserted through the grill for moving the damper in either direction.

HERBERT F. CURTIS.
